UNITED STATES PATENT OFFICE.

WILLIAM COOK ROGERS, OF PIQUA, OHIO.

IMPLEMENT-HANDLE.

1,116,739.

Specification of Letters Patent. Patented Nov. 10, 1914.

Application filed April 3, 1914. Serial No. 829,175.

To all whom it may concern:

Be it known that I, WILLIAM COOK ROGERS, a citizen of the United States, and residing at Piqua, in the county of Miami 5 and State of Ohio, have invented a new and useful Implement-Handle, of which the following specification is a full disclosure.

My invention relates to an improvement in handles, primarily of a type known as D 10 handles in which the upper end thereof is bifurcated to receive a transverse handle-piece between the furcations. This form of handle is usually made of wood and is commonly associated with shovels and other agricultural hand tools.

The object of this invention is to provide a fastener for handle joints adapted to be seated in the abutting surfaces of the handle-piece and furcations.

Another object is to provide a fastener for handle joint comprising an annulus having opposing roughened surfaces adapted to engage the abutting surfaces of the abutting members to be joined, with a further object 25 of wholly embedding the annulus or ferrule within the handle-piece.

Other novel features of construction and arrangement of parts are made apparent by the accompanying drawings, illustrating a 30 preferred form of embodiment of this invention, in which like characters of reference denote corresponding parts throughout the several views, of which:—

Figure 1 is a front elevation partly in section of the upper end of a bifurcated or D handle showing my improved fastening device applied thereto. Fig. 2 is a section on line 2—2 of Fig. 1, and Fig. 3 is a view partly in section showing the device applied 40 in a different manner to another form of handle.

Referring to Figs. 1 and 2 it will be noted that the handle is bifurcated to form two oppositely disposed limbs or furcations 1 and 45 2, having a transverse handle-piece 3 supported between their upper ends, said furcations and handle-piece being secured together as a unit by a binding rod or bolt 4.

6 represents a thin-metal annulus having 50 opposing roughened edges preferably in the form of tangs or teeth 7 and 8, as shown. The body portion of the annulus 6 is completely embedded in a groove or annular recess 9 formed in the abutting surface 10 of 55 the handle-piece 3. During the assembling of the parts the tangs 8 seat into the mate-

rial at the base or bottom of the groove 9 and the opposing tangs 7 on the opposite edge of the annulus seat into the material of the abutting surface of the limbs or furcations of the handle. These opposing roughened edges or tangs of the annulus serve as a means for preventing the handle-piece 3 from turning, and the annulus by reason of its tubular formation functions as 65 a ferrule preventing splitting of the joined members.

Fig. 3 shows a handle-piece 11 as having a single abutting surface 12 provided with a groove or recess 13. The abutting surface 70 of the supporting member 14 is provided with a corresponding groove or recess 15. The annulus 16 is partly embedded in each of these grooves thereby dividing its reinforcing function more equally between the 75 joined members. The opposing tangs 17 and 18 seat in the material at the base of their companion grooves 15 and 13, and serve the same purpose as the tangs 7 and 8 of the annulus 6, of the D handle previously 80 described.

In the preferred embodiment illustrated the annulus is entirely concealed or embedded in the wood of the handle and does not present any metal or edges to the injury of the user's hands or detract from the finish of the handle. While I have shown my invention as applied to handles its adaptation for use in joining two members of any form having abutting surfaces is obvious, and where it is desirable to prevent any relative turning of the members. It is also obvious that the annulus may assume a shape other than circular as shown, to conform to the shape of the handle-piece. 95

Having thus described my invention I claim as new and desire to secure by Letters Patent of the United States:—

1. A device of the nature disclosed combining a bifurcated handle having its furcations in separated and spaced relation, a transverse handle-piece interposed between the furcations, a tubular metal annulus embedded in the end of the handle-piece, and provided with opposed roughened edges 100 adapted to seat in the material of the furcations and handle-piece, and a binding rod passing through the furcations and handle-piece to clamp them together. 105

2. A device of the nature disclosed combining a handle-piece, a supporting member therefor, a tubular metal annulus em- 110

bedded in the abutting surfaces of the handle-piece and supporting member and provided with opposing roughened edges adapted to seat in the material of the handle-piece and supporting member, and a rod passing through the several parts to bind them together.

3. In a bifurcated implement handle, the combination of a transverse handle-piece supported between the furcations thereof, a rod passing through the furcations and handle-piece to bind them together, said handle-piece being provided with a recess in each of its abutting surfaces formed concentric to

the binding rod, a tubular metal annulus 15 wholly embedded in each recess and tangs formed on opposite edges of the annuli adapted to seat in the material of the furcations and handle-piece to prevent the handle-piece from turning.

20 In witness whereof, I hereunto subscribe my name, as attested by the two subscribing witnesses.

WILLIAM COOK ROGERS.
